RAY C. NEWHOUSE, OF MILWAUKEE, WISCONSIN, ASSIGNOR TO ALLIS-CHALMERS COMPANY, OF MILWAUKEE, WISCONSIN, A CORPORATION OF NEW JERSEY.

CRUSHER.

1,065,332.

Specification of Letters Patent. Patented June 17, 1913.

Application filed July 22, 1912. Serial No. 711,333.

To all whom it may concern:

Be it known that I, RAY C NEWHOUSE, a citizen of the United States, residing at Milwaukee, in the county of Milwaukee and State of Wisconsin, have invented a certain new and useful Improvement in Crushers, of which the following is a specification.

This invention relates to improvements in the construction of crushers for rock, ore, and similar substances.

An object of the invention is to provide a crusher in which material is crushed by the direct approach of at least one of a pair of crushing members toward the other, the feeding of the material through the crushing chamber being accomplished by so rotating the crushing members that centrifugal force will automatically advance the material from the feed to the discharge end of the crusher.

Another object of the invention is to provide a crusher in which the crushing is accomplished by admitting fluid under pressure between opposed surfaces carried by the crushing members.

A clear conception of an embodiment of the invention may be had by referring to the drawing accompanying and forming part of this specification in which like reference characters designate the same parts in the various views.

Figure 1 is a transverse vertical section through a fluid pressure actuated crusher. Fig. 2 is an end view of the crusher disclosed in Fig. 1, the relief valve, tank and piping at the end of the crusher having been omitted in order to more clearly disclose other details of the apparatus.

The crusher consists essentially of a pair of opposed crushing members 3, 8, which are provided with corrugated liners 6, 7, respectively. The crushing chamber formed between the corrugated liners 6, 7, has the feed hopper 1 directed into its mid-portion and is provided with a free discharge passage adjacent the peripheries of the liners 6, 7. The housing 2 which is provided with a discharge opening 10 at its lower end, incloses the crushing elements.

The hollow outer shaft 12 is supported in the bearing 11 of the frame 15 and has an outwardly projecting flange 4 formed inte-

gral with one of its ends. The crushing member 3 is fixed to the flange 4 of the hollow shaft 12 by means of a series of bolts 55 which pass through the member 3 and flange 4 and clamp these members against the ends of distance pieces or sleeves 5 preferably sleeved on the bolts. The inner shaft 9 is supported within and concentrically with 60 the outer shaft 12 and has the crushing member 8 formed integral therewith. A means for preventing relative rotation between the members 3, 8, is provided in the form of a spline 13 which is secured to the inner shaft 65 9 and is adapted to slide in a recess formed in the outer shaft 12. Such means for preventing relative rotation between the crushing members 3, 8, is necessary only when the corrugations of the liners 6, 7, project within 70 each other, and would not be necessary if uncorrugated liners 6, 7, were used.

The outer shaft 12 is provided with an outwardly projecting flange 50 to which the casing 26 and the driving pulley 25 are secured by any suitable means, such as a series of cap screws 51. The pulley 25 is connected with the motor 47 by means of a belt 45. The piston 24 is secured to the end of the inner shaft 9 and is adapted to fit snugly 75 within the bore of the casing 26. The packing ring 28, carried by the piston 24, coacts with the bore of the casing 26. The main pressure chamber 27 is formed between a surface of the piston 24 and an opposed surface of the casing 26. The spring 14 which is normally under compression, coacts with its one end against an end surface of the piston 24 and with its opposite end against an end surface of the outer shaft 12, thus 80 tending at all times to force the crushing member 8 away from the crushing member 3.

The displacement piston or plunger 30 is adapted to be reciprocated in the displacement chamber 37 of the displacement cylinder 29 by means of a crank shaft 32 to which the plunger 30 is connected by means of the connecting rod 31. The crank shaft 32 is adapted to be rotated by means of a motor 47 which drives the pulley 33 through a 85 belt 46. The displacement chamber 37 is connected, by means of an open conduit, directly with the chamber 27 formed in the casing 26. The joint between the displace-

ment cylinder 29 and the casing 26 is packed by means of a suitable stuffing box 38. The valve or cock 35 is adapted to exhaust air from the displacement chamber 37 and the chamber 27.

6 The supply pump 42, which is driven directly and continuously by the crank shaft 32, has a suction conduit 44 which connects with the fluid supply reservoir 16 formed in the frame 15 directly below the bearing 11. The supply conduit 44 is controllable by means of a manually operable needle valve 43. The discharge pipe 34 of the pump 42 is divided into two branches 36, 39, the one branch 36 of which connects directly with the interior of the displacement piston chamber 37. The second branch pipe 39 connects through a pressure relief valve 40 with a relief reservoir or tank 41. The lower end of the relief tank 41 connects directly with the suction side of the supply pump 42.

10 The piston 24 carries at one portion thereof a small piston 22 which has an axis parallel with that of the crushing members 3. 15 8, and closely fits a bore in the flange 50 of the outer shaft 12. A passage 21 is formed through the outer shaft 12 and flange 50 and connects with the bore in which the small piston 22 is fitted. The connection of the 20 passage 21 with this bore is controlled by means of inlet and discharge valves 56, 55. The passage 21 connects at its one end with the periphery of the chamber 23 formed between the piston 24 and the flange 50, and 25 with its opposite end with a groove 20 formed in the shaft 12 between the bore of the hollow shaft 12 and the outer surface of the inner shaft 9. The groove 20 is connected with an annular groove 18 adjacent 30 the inner shaft 9, which is connected by means of a discharge conduit 19 with the groove 52 formed in the bearing 11. The 35 groove 52 is direct connected by means of a conduit 17 with the fluid supply reservoir 16. The fluid within the reservoir 16 may 40 be replenished by removal of the filling 45 plug 48.

During the normal operation of the crusher the operating chamber 27, the displacement chamber 37, and the conduit connecting these chambers are filled with a fluid, preferably oil. The crushing member 3 is rotated by means of the belt 45 driven by the motor 47 and coacting with the pulley 25. The displacement piston 30 is reciprocated by means of the belt 46 driven by the motor 47 and coacting with the pulley 33. As the pulley 33 is considerably smaller than the pulley 25, the plunger 30 will complete a number of reciprocations during one revolution of the crushing members 3, 8. The crushing member 8 is positively rotated with the crushing member 3 through the spline 13. The material to be crushed is admitted to the mid portion of the crushing

chamber formed between the corrugated liners 6, 7, through the inlet hopper 1. As the displacement plunger 30 reciprocates it alternately forces fluid from the displacement chamber 37 into the chamber 27, during its forward stroke, and returns this fluid to the chamber 37 during the return stroke. In forcing the fluid from the chamber 37 into the chamber 27, the plunger 30 compresses the fluid and exerts a pressure 70 against the piston 24 in a direction toward the crushing members 3, 8, and against the opposed surface of the casing 26 in a direction away from the crushing members. This forward pressure against the piston 24, and 75 rearward pressure against the casing 26, causes the crushing member 8 to directly approach the member 3, thereby crushing the material within the crushing chamber by the direct approach of the crushing members 80 toward each other. During the return stroke of the displacement plunger 30 and the resulting withdrawal of fluid from the chamber 27, the spring 14 as well as the slight suction produced within the chamber 27, cause the piston 24 and crushing member 8 to recede from the member 3. During 85 this recession of the member 8 the material within the crushing chamber is forced toward the peripheries of the corrugated liners 6, 7, by the action of centrifugal force. After successive approaches and recessions 90 of the crushing member 8 toward and away from the member 3, the material is eventually reduced sufficiently to permit its free 95 passage from the discharge opening at the peripheries of the liners 6, 7.

100 Due to the enormous fluid pressure within the chamber 27 during the crushing stroke, considerable leakage of the fluid from within the chamber 27 past the piston 24 and packing ring 28 will take place. In order to maintain a constant volume of the fluid within the chambers 27, 37, the pump 42 is driven continuously and its suction inlet 44 is throttled by means of the needle valve 43 to permit the passage of an amount 105 of fluid through the pump 42 which is just sufficient to replace the leakage. If air is entrained into the chambers 27, 37, it should 110 be withdrawn through the air cock 35, since the compression of such entrained air during the crushing stroke of the crushing member 8 would lower the efficiency of the machine. If by accident some unbreakable 115 material, as for instance a bolt, is thrown into the crushing chamber, the forward crushing motion of the crushing member 8 will be suddenly arrested and the pressure 120 within the chambers 27, 37, will rise to a sufficient extent to cause the safety valve 40 to open and by-pass a portion of the fluid from the displacement chamber 37 through the branch pipes 36, 39, through the valve 40, into the chamber 41. The fluid thus by- 125 130

passed will be taken from the chamber 41 directly into the suction of the pump 42 and returned to the displacement piston chamber 37. The fluid which leaks past the piston 24 and packing ring 28 into the chamber 23 is held against the peripheral surfaces of the chamber 23 by the action of centrifugal force thereon. The reciprocation of the piston 24 causes the small piston 22 to reciprocate within the bore formed in the flange 50. During the motion of the small piston 22 away from the crushing member 3, the flap valve 56 in the passage 21 and nearest the periphery of the flange 50 is opened and fluid is withdrawn from the periphery of the chamber 23 to the chamber formed between the two small flap valves 56, 55.

During the forward or crushing stroke of the large piston 24 and the small piston 22, the oil contained in the chamber formed between the flap valves 56, 55, is forced past the flap valve 55 which is nearer the center of the machine, into the passage 21 and groove 20. While in the groove 20 the oil lubricates the bearing between the inner shaft 9 and the outer shaft 12. From the groove 20 the oil passes into the annular groove or recess 18 from which it passes through the conduit 19 to the grooves 52 of the bearing 11. After lubricating the bearing 11, the oil passes through the conduit 17 to the oil supply reservoir 16. From the oil supply reservoir 16 the fluid is eventually drawn through the suction conduit 44 to the pump 42.

By forming the liners 6, 7, with the corrugations of one extending into those of the other, positive means for preventing the free passage of flat pieces of rock through the crushing chamber is provided. It should also be noted that the fluid of the crusher actuated system is entirely inclosed, thus preventing the admission of dust or gritty material thereto. The replenishing of the leakage fluid is entirely automatic after the needle valve 43 has been properly set. The safety valve 40 and tank 41 provide a simple and efficient means for preventing injury to the crushing elements in case a piece of iron or similar material is admitted to the crushing chamber.

It is not essential to employ a motor 47 as disclosed for driving the device, as any other desirable power supplying means might be substituted.

By using an incompressible fluid such as oil, the stroke of the crushing member 3 will be maintained constant unless the stroke of the displacement plunger 30 is varied. The use of oil as a working fluid also provides a simple and efficient means for lubricating the working parts.

It should be understood that it is not de-
65 sired to be limited to the exact details of

construction shown and described, for obvious modifications will occur to a person skilled in the art.

It is claimed and desired to secure by Letters Patent,

1. A crusher comprising a pair of rigid crushing members symmetrically disposed about a common axis and having crushing surfaces, said members being rotatable to feed material along the crushing surfaces thereof, means for permitting fluid pressure to act directly between said members for taking up the reactive thrust induced by crushing and for causing said crushing surfaces to relatively approach each other. 70

2. A crusher comprising a pair of rigid crushing members symmetrically disposed about a common axis and having crushing surfaces, said members being rotatable to feed material along the crushing surfaces thereof, means for permitting fluid pressure to act directly between said members for taking up the reactive thrust induced by crushing and for causing at least one of said members to move along said axis to crush 80 material. 85

3. A crusher comprising a pair of rigid co-axial members symmetrically disposed about their common axis and having crushing surfaces, said members being rotatable only in the same direction to feed material along the crushing surfaces thereof, and means for effecting the relative approach of said crushing surfaces to crush material. 95

4. A crusher comprising a pair of rigid co-axial members symmetrically disposed about their common axis and having crushing surfaces, said members being rotatable only in the same direction to feed material along the crushing surfaces thereof, and means for 100 effecting the relative approach of said members along their axes to crush material. 105

5. A crusher comprising a pair of rigid crushing members symmetrically disposed about a common axis and having crushing surfaces, said members being rotatable to feed material along the crushing surfaces thereof, and means for permitting liquid under pressure to act directly between said members for moving one of said members 110 toward the other to crush material. 115

6. A crusher comprising a pair of rigid crushing members symmetrically disposed about a common axis and having crushing surfaces, said members being rotatable to feed material along the crushing surfaces thereof, and means for permitting liquid under pressure to act directly between said members for moving one of said members along said axis to crush material. 120 125

7. A crusher comprising a pair of rigid crushing members symmetrically disposed about a common axis and rotatable to feed material along the crushing surfaces, and means for permitting liquid under pres- 130

sure to act directly between said members for moving one of said members to crush material.

8. A crusher comprising a pair of rigid crushing members symmetrically disposed about a common axis and having crushing surfaces, said members being rotatable to feed material along the crushing surfaces thereof, a positive driving connection between said members, and means for permitting fluid pressure to act directly between said members for moving at least one of said members to crush material.

9. A crusher comprising a pair of rigid crushing members symmetrically disposed about a common axis, fluid pressure actuated means for moving at least one of said members toward the other to crush material, and mechanical means coacting directly between portions of said members for forcing said members apart.

10. A crusher comprising a pair of rotatable crushing members having constantly inter-meshing corrugations, and fluid pressure actuated means effecting the relative approach of said members to crush material.

11. A crusher comprising a pair of rigid opposed corrugated crushing members symmetrically disposed about a common axis and having crushing surfaces, said members being rotatable to feed material along the crushing surfaces thereof, a positive driving connection between said members, and fluid pressure actuated means for moving at least one of said members toward the other to crush material.

12. A crusher comprising a pair of opposed corrugated crushing members having crushing surfaces, said members being rotatable to feed material along the crushing surfaces thereof, a positive driving connection between said members, and means for moving at least one of said members toward the other to crush material.

13. In a crusher, a pair of opposed crushing members, a cylinder carried by one of said members, a piston carried by the other of said members, and means for admitting fluid pressure to the interior of said cylinder whereby said piston is moved to effect crushing.

14. A crusher comprising a pair of rigid crushing members symmetrically disposed about a common axis, fluid pressure actuated means for moving at least one of said

members toward the other to crush material, and spring means coacting directly between portions of said members for moving said members away from each other.

15. In a crusher, a pair of opposed crushing members, a cylinder carried by one of said members, a piston carried by the other of said members, and means for alternately admitting and exhausting fluid to and from the interior of said cylinder whereby said piston is reciprocated and crushing is effected.

16. In a crusher, a pair of opposed crushing members, a casing carried by one of said members, a piston carried by the other of said members, means for admitting fluid to the interior of said casing and against said piston whereby said piston is moved to crush material, and automatic means for by-passing said fluid when the motion of said piston is suddenly arrested.

17. In a crusher, a pair of crushing members, means for forcing fluid between opposed surfaces carried by said members whereby relative motion between the members to crush material is produced, and means for replenishing the leakage of fluid.

18. A crusher comprising a pair of crushing members having crushing surfaces, said members being rotatable to feed material along the crushing surfaces thereof, means for taking up between the members the reactive thrust induced by crushing, and means for establishing fluid pressure acting directly on portions of said members for causing said crushing surfaces to relatively approach each other.

19. A crusher comprising a pair of crushing members having crushing surfaces, said members being rotatable to feed material along the crushing surfaces thereof, means for taking up between the members the reactive thrust induced by crushing, and means for establishing fluid pressure acting directly on portions of said members for causing at least one of said members to move along its axis to crush material.

In testimony whereof, the signature of the inventor is affixed hereto in the presence of two witnesses.
